COMPRESSOR

Stephen Vorech and Stephen Johnson, Jr., Pittsburgh, Pa., assignors to Bendix-Westinghouse Automotive Air Brake Company, Pittsburgh, Pa., a corporation of Delaware

Application September 11, 1931, Serial No. 562,303

19 Claims. (Cl. 230—206)

This invention relates to compressors, and more particularly to compressors employed as part of the air brake and air starter equipment of automotive vehicles.

It has been proposed to mount the compressor at the side of the engine of the vehicle, and further to lubricate the moving parts thereof from the force feed lubrication system of the engine. It is the principal object of the invention to improve such structural features, and to this end there is suggested a very rigid mounting for the compressor, the compressor crank case and engine crank case being so constructed and arranged as to effectively cooperate in providing the desired mounting as well as providing a means for conducting the oil from the engine to the compressor.

In the arrangements disclosed, the oil, after lubricating the compressor parts, is permitted to drain back to the engine case by gravity through relatively large intercommunicating openings in the respective cases.

Another object of the invention is to provide means for sealing the oil from the end bearings of the compressor, particularly of the ball type, in a structure for lubricating the connecting rod bearings and wherein the oil is transmitted through ducts in the crank shaft.

Other objects of the invention and desirable details of construction will become apparent from a reading of the following detailed description taken in connection with the accompanying drawings, in which:

Figure 1 is a vertical sectional view, taken on line 1—1 of Figure 2, through an automotive air compressor embodying certain features of our invention;

Figure 2 is an end view of the compressor of Figure 1, the mounting being shown in section;

Figure 3 discloses in detail the oil seal construction for the compressor of Figure 1;

Figure 4 is a view similar to Figure 1 showing a different type of mounting construction, the section being taken on line 4—4 of Figure 5;

Figure 5 is a view similar to Figure 2 disclosing the mounting of Figure 4 in greater detail;

Figure 6 discloses a further modification of compressor mounting;

Figure 7 discloses in combination with conventional compressor structure one form of end bearing oil seal construction.

Figure 7A discloses a modified form of drive for the compressor disclosed in Figure 7;

Figure 8 discloses in detail a further modified form of mounting structure; and

Figure 9 discloses another modification of oil seal for the end bearing.

In that embodiment of our invention disclosed in Figures 1 and 2 there is shown a compressor structure of generally conventional type comprising cylinders 10 and 12 housing reciprocable pistons 14 connected by the usual connecting rods 16 to a compressor crank shaft 18 by the usual bearings 20.

The invention is particularly concerned with the means for lubricating the aforementioned connecting rod bearings, and to this end the force feed lubricating system of the engine may be employed to useful advantage, all in combination with a very rigid mounting for the compressor, the latter also being a feature of our invention. As disclosed in detail in Figures 1 and 2, interconnecting ducts 22, 24, 26 and 28 in the engine case 30 and lower half 32 of the compressor case provide a conduit for the oil, under a constant head of pressure from the engine lubricating system, and which oil is communicated by duct 34 direct to a chamber 36 adjoining an end bearing of the compressor crank shaft. Ducts 38, 40 and 42 are provided, in the compressor case, to permit the compressor to be reversed on its mounting and maintain the aforementioned oiling system. A duct 44 is also provided as a drain and is normally closed by plug 46. An axially directed opening 48 of comparatively small bore serves to transmit the oil from chamber 36 to the interconnecting ducts 50, 52 and 54 in the crank shaft 18, which ducts extend to the connecting rod bearings 20 to lubricate the same.

Referring now to the mounting of the compressor aforementioned, the lower half 32 of the compressor crank case is formed as a boss cast with the engine case 30 and projects laterally therefrom as clearly disclosed in Figure 2. The upper half of the compressor case is bolted or otherwise securely fixed to the lower half by fastenings 56. The compressor is thus rigidly mounted in position. It will furthermore be noted that the hollow interior of the lower half of the compressor case provides a relatively large gravity return to the engine case for the oil thrown from the connecting rod bearings.

In order to insure an oil-tight joint between the engine and compressor crank case, a recess 11 is formed in the base of the compressor crank case adapted to receive a suitable gasket 13. The recess 11 is formed interiorly of the peripheral edge of the compressor crank case so that the edges of the gasket are enclosed and metal to metal contact is provided between the engine 110

and compressor crank cases at the periphery of the joint therebetween. The gasket 13 is provided with openings 15 registering with the oil ducts 28, 42 and 44 to provide an oil-tight passage when the parts are assembled. In mounting the compressor on the engine crank case a gasket 13 of any suitable material, such, for example, as cork, is set in the recess 11 the thickness of the gasket being slightly greater than the depth of the recess. The fastening bolts are then inserted and drawn down tightly compressing the gasket until the metallic rim surrounding the recess is in direct contact with the engine crank case, the gasket then being tightly pressed between the compressor and engine crank cases to form an oil-tight seal both around the oil ducts and between the engine and compressor crank cases. The metal to metal contact between the engine and compressor crank cases protects the gasket, provides a more rigid joint between the compressor and the engine and enables the compressor to be located very accurately, thus insuring proper alignment between the compressor and its drive means.

The end bearings of the crank shaft are preferably of the ball type and with the construction shown, that is with the oil fed direct through the shaft, some means must be provided for sealing off the chamber 36 from the end bearing as well as the driven end or stub shaft 58. To this end a sealing member 60, which may be a washer of leather or equivalent material, is firmly pressed at its outer periphery against the outer face of the ball race 62 by a spring 64. At its inner periphery the washer or gasket is urged into contact with the race by the four prongs of a spring washer member 66 securely attached to the inner face of bearing cap 68. A standard form of gland 70 may be provided to obviate the loss of oil outwardly of the shaft. The springs 64 and 66 also serve to maintain the ball bearing structure firmly in position. A very compact oil seal structure is thus provided permitting a direct communication from the engine lubricating system to a chamber adjacent the end bearing and thence direct to the connecting rod bearings.

A recess 71 similar to recess 11 shown in Fig. 1 is provided in the compressor crank case adapted to receive a gasket 73, the gasket having openings 75 registering with the oil ducts. The recess 71 is formed interiorly of the periphery of the compressor crank case so that the outer periphery of the gasket is entirely enclosed and metal to metal contact is provided at the periphery of the joint between the engine and compressor crank cases.

As disclosed in Figures 4 and 5, the lower half 72 of the compressor crank case may be constructed to be bolted direct to a boss 74 on the engine case by fastenings 76. In Figure 4 we have also disclosed a slightly different form of oil seal wherein the gasket 78 is secured to the outer ball race by a cap member 80, the cap thus serving, together with the spring 84, to hold the gasket in position.

In Figure 6 there is disclosed a further modification of compressor mounting wherein an inclined boss 86 on the compressor case complements a similar boss 88 on the engine case, the two being rigidly secured together by bolts or equivalent fastenings 90. In both types of mountings disclosed in Figures 5 and 6 the oil thrown from the connecting rod bearings is returned to the engine case and thence to the engine sump

by means of the intercommunicating openings in the compressor and engine cases.

In Figure 7 there is disclosed another type of oil seal and end bearing structure, juxtaposed and similar ball bearing units 92 being separated by a collar 94 bored at 96 to conduct the lubricating oil from the chamber defined by the units to a groove 98 in a timing gear driven crank shaft 99 and thence via ducts in the shaft to the connecting rod bearings. A light spring 100 serves, in conjunction with caps 102 and the pressure of the oil, to retain the sealing gaskets 104 in position. If desired, a small hole 106 may be provided in the outer gasket 104 to pass lubricant to the outer bearing unit. The inner bearing units in all of the modification disclosed are lubricated by the spray of oil thrown from the connecting rods.

If desired, the crank shaft of Figure 7 may be driven by a V-belt pulley 101 keyed to a stub shaft 103 journaled in bearing 105 and connected to the crank shaft at 107, all as disclosed in Figure 7A.

In Figure 8 there is disclosed a further modified form of sealing and bearing structure wherein the thickness of the bearing cap 108 is such as to completely cover the side face of the bearing unit 110, a small annular pocket 112 in communication with the shaft duct 114 and supply duct 116 serving to provide a reservoir for the oil. A gasket 118 is clamped between the cap and the bearing unit to obviate ingress of oil to the unit, and a gland structure 120 completes the sealing structure.

There is disclosed in Figure 9 a modified form of oil return structure wherein a baffle 122 functions, in conjunction with the oil 124, pocketed in the base of the compressor crank case at 125, to obviate gaseous communication between the engine and compressor cases. The fumes from the engine case are thus prevented from entering the compressor case. An opening 126 in the engine case serves to drain the surplus oil in the compressor case back to the engine case and thus maintain a constant level of oil in the pocket 125. A breather 127 is provided in the compressor case to compensate for any back pressure which may be developed in the case.

It is not our intention to limit the scope of the invention to the particular structures described and disclosed, nor otherwise than by the terms of the appended claims.

We claim:

1. A compressor structure comprising, in combination with a crank case of an internal combustion engine, an integral projection extending outwardly from said case forming the lower half of the crank case of a compressor, said projection being hollow to provide free communication between said engine case and said compressor case, together with an upper compressor crank case member detachably secured to said lower crank case member, said crank case members being provided with a plurality of intercommunicating ducts connected to one end bearing of the compressor at one end of the series of ducts and to the pressure lubricating system of the engine at the other end of said series.

2. In a compressor structure, upper and lower crank case members together constituting a crank case of a compressor, said upper member being provided in its side walls with oppositely inclined oil ducts, other ducts extending substantially right angularly of said inclined ducts and a longitudinally extending duct interconnecting said

- last mentioned ducts, all of said aforementioned ducts intercommunicating to provide a conduit for the transference of a lubricant and further providing a system of ducts symmetrically arranged in the crank case member. 5 80
3. A compressor mounting structure comprising a hollow angularly extending lower half part of a one piece compressor crank case member, a boss projecting from one side of the crank case of an internal combustion engine about an opening therein and means for detachably securing said compressor crank case member to said engine boss portion to complete the mounting structure, said parts being provided in the thickness 10 25 15 15 of their side walls with intercommunicating ducts providing a means for transmitting lubricant to moving parts of the compressor.
4. A compressor mounting comprising, in combination with the crank case of an internal combustion engine, said case having a hollow projection integral therewith and extending laterally therefrom, a baffle member secured to said projection and extending inwardly into the hollow thereof, together with an upper casing member 20 25 30 35 detachably secured to the peripheral edge of said aforementioned projection and constituting therewith the crank case of a compressor.
5. A compressor mounting comprising, in combination with the crank case of an internal combustion engine, said case having a hollow projection integral therewith and extending laterally therefrom, a baffle member secured to said projection and extending inwardly into the hollow thereof, together with an upper casing member 35 40 45 50 55 60 65 70 75 80 85 90 95 100 105 110 115 120 125 130 135 140 145 150 detachably secured to the peripheral edge of said aforementioned projection and constituting therewith the crank case of a compressor, the wall of said engine case opposite said projection being provided with an opening adjacent said baffle member.
6. In a compressor having a crank case and a crank shaft therein, lubricating means comprising a ball bearing unit interposed between said case and shaft at one end of the latter, an end bearing cap member secured to said case, said cap member being recessed in one end thereof to provide, with said shaft and bearing, an oil reservoir, an oil sealing gasket positioned against one side face of said bearing unit and a plurality of spring members arranged and tensioned between said cap and gasket, and urging the latter into engagement with said unit. 45 50 55 60 65 70 75 80 85 90 95 100 105 110 115 120 125 130 135 140 145 150
7. In a compressor having a crank case and a crank shaft therein, lubricating means comprising a ball bearing unit interposed between said case and shaft at one end of the latter, an end bearing cap member secured to said case, said cap member being recessed in one end thereof to provide, with said shaft and bearing, an oil reservoir, an oil sealing gasket positioned against one side face of said bearing unit, and a plurality of spring members arranged and tensioned between said cap and gasket and urging the latter into engagement with said unit, one of said 60 65 70 75 80 85 90 95 100 105 110 115 120 125 130 135 140 145 150 spring members being provided with a plurality of prongs contacting with said gasket at its inner periphery.
8. In a compressor having a crank case and a crank shaft therein, lubricating means comprising a plurality of spaced ball bearing units positioned in a recess formed in the crank case at one end of the crank shaft, a spacer collar member interposed between said units, gasket members positioned in the space between said units and against the side 70 75 80 85 90 95 100 105 110 115 120 125 130 135 140 145 150 faces of the same together with yieldable means for urging said gasket firmly into contact with said units.
9. In a compressor having a crank shaft, lubricating means comprising a bearing unit supporting one end of said crank shaft, a chamber surrounding said crank shaft adjacent said bearing unit, a passage for conducting lubricant into said chamber, a lubricant sealing gasket positioned against said bearing unit to prevent leakage of said lubricant from said chamber through said unit, and a second passage for conducting lubricant from said chamber into said crank shaft. 80 85 90 95 100 105 110 115 120 125 130 135 140 145 150
10. In a compressor having a crank shaft, lubricating means comprising a bearing unit supporting one end of said crank shaft, a chamber surrounding said crank shaft adjacent said bearing unit, a passage for conducting lubricant into said chamber, a lubricant sealing gasket positioned against said bearing unit to prevent leakage of said lubricant from said chamber through said unit, resilient means in said chamber for holding said gasket against said bearing unit, lubricant sealing means between said chamber and crank shaft to prevent leakage of lubricant from said chamber along the crank shaft, and a passage for conducting lubricant from said chamber into said crank shaft. 90 95 100 105 110 115 120 125 130 135 140 145 150
11. In a compressor having a crank case and a crank shaft, lubricating means comprising a pair of spaced bearing units mounted in a chamber in said crank case and supporting one end of said crank shaft, a passage for conducting lubricant into said chamber between said bearing units, sealing gaskets positioned against said bearing units to prevent flow of lubricant from said chamber through said bearing units, and a second passage for conducting lubricant from said chamber into said crank shaft. 105 110 115 120 125 130 135 140 145 150
12. In combination with an internal combustion engine having a crank case and a pressure lubricating system, a compressor comprising a crank case adapted to be directly secured to the crank case of the engine, a crank shaft in said compressor crank case, and intercommunicating ducts in said compressor and engine crank cases, the duct in said engine crank case communicating with the pressure lubricating system of the engine. 115 120 125 130 135 140 145 150
13. In combination with an internal combustion engine having a crank case and a pressure lubricating system, a compressor comprising a crank case adapted to be directly secured to the crank case of the engine, a crank shaft in said compressor crank case, intercommunicating ducts in said compressor and engine crank cases, the duct in said engine crank case communicating with the pressure lubricating system of the engine, and the duct in said compressor crank case communicating with the compressor crank shaft, and an intercommunicating passage between said compressor and engine crank cases for returning excess lubricant from said compressor crank case to said engine crank case. 125 130 135 140 145 150
14. In combination with an internal combustion engine having a crank case, a compressor comprising a crank case adapted to be directly secured to said engine crank case, registering openings in said compressor and engine crank cases, one of said crank cases being recessed around said openings, and a gasket mounted in said recess, the outer periphery of said gasket being wholly contained within said recess. 140 145 150
15. In combination with an internal combustion engine having a crank case, a compressor 150

- comprising a crank case adapted to be directly secured to said engine crank case, registering openings in said compressor and engine crank cases, and a gasket surrounding said openings and disposed between said engine and compressor crank cases, the outer portion of said compressor crank case being in direct contact with said engine crank case. 18. In a compressor having a crank case and a crank shaft, lubricating means comprising a pair of spaced bearing units mounted in a chamber in said crank case and supporting one end of said crank shaft, a passage for conducting lubricant into said chamber between said bearing units, means positioned between said units for preventing escape of lubricant from said chamber through said units, and a second passage for conducting lubricant from said chamber into said crank shaft. 80
16. In combination with an internal combustion engine having a crank case, a compressor comprising a crank case adapted to be directly secured to said engine crank case, registering openings in said compressor and engine crank cases, one of said crank cases being recessed around said openings, a gasket mounted in said recess, the outer periphery of said gasket being wholly contained within said recess, intercommunicating ducts in said engine and compressor crank cases, and openings in said gasket registering with said ducts. 19. In a compressor having a crank case and a crank shaft, lubricating means comprising a pair of spaced bearing units mounted in the chamber in said crank case and supporting one end of said crank shaft, an annular spacer member positioned between said bearing units and carried by said crank shaft, a passage for conducting lubricant into said chamber between said bearing units, means positioned between said units for preventing escape of lubricant from said chamber through said units, a passage in the crank shaft, and means for conducting lubricant to said crank shaft passage including a plurality of ports through said spacer member. 85 90 95
17. In combination with an internal combustion engine having a crank case, a compressor including a crank case adapted to be directly secured to said engine crank case, intercommunicating ducts in said engine and compressor crank cases, and a gasket between said engine and compressor crank cases having an opening therethrough which communicates with said ducts, a portion of said compressor crank case being in direct contact with said engine crank case. 100
